port Beach, Calif., assignors to Smith Industries Interna-
tional, Inc., Los Angeles, Calif., a corporation of
California

Filed Nov. 7, 1966, Ser. No. 592,518
44 Claims. (Cl. 299—60)

ABSTRACT OF THE DISCLOSURE

A tunneling machine having two separate cutting heads each of which cuts its own individual portion of the tunnel face, and each of which is driven by its own separate drive means so as to permit individual control of the cutting action on the different portions of the tunnel face; each cutting head being driven in an oscillating action by a hydraulic linear accelerator which is disposed parallel to the plane of oscillation of the cutting head and coupled between the frame of the machine and the cutting head.

Background of the invention

This application is a continuation-in-part of our co-pending application Ser. No. 308,843, filed Sept. 13, 1963, and entitled, Oscillating Tunneling Machine, and now abandoned.

It is well known in the art that a variety of earth formations are encountered in tunneling operations. These earth formations may be broadly classified as relatively soft homogeneous formations, relatively hard homogeneous formations, and non-homogeneous formations. Relatively soft homogeneous formations are those which consist of relatively soft material, such as sand, clay, shale, soil or the like, and present a generally homogeneous tunnel face, that is a tunnel face consisting substantially entirely of such soft material. Relatively hard homogeneous formations are those which consist of relatively hard material, such as rock, granite, or the like, and present a generally homogeneous tunnel face of such hard material. Non-homogeneous formations are those which consist of both relatively hard and soft materials and present a tunnel face composed partly of relatively hard material and partly of relatively soft material. As will appear from the ensuing description, the improvements contributed by the present invention may be employed, to advantage, in tunneling machines for use in all three of these types of earth formations. However, the invention is particularly concerned with tunneling operations in relatively soft homogeneous formations and non-homogeneous formations. In this regard, for example, the preferred embodiment of the invention is uniquely constructed and arranged for use in both of these latter types of formations.

Generally speaking, a typical conventional tunneling machine has a frame mounting a forward rotary cutter, or cutting wheel, means for driving the cutting wheel in rotation, means for feeding the cutting wheel forwardly against the tunnel face to effect a cutting action on the face, and conveyor means for removing the dirt, rock, sand, and other debris, herein referred to simply as debris, removed by the cutting wheel. In some cases, the cutting wheel is fed against the tunnel face by driving the entire machine structure, that is machine frame and cutting wheel, forwardly as a unit in stepwise fashion. In other cases, the cutting wheel is fed into the tunnel face by alternately driving the cutting wheel forwardly relative to the frame in a feed stroke and thereafter driving the frame forwardly relative to the cutting wheel in a repositioning stroke, thus to condition the machine for the following

2

feed stroke of the cutting wheel. In many tunneling operations, particularly those which involve driving a tunnel through relatively soft formations, a tunnel liner is installed, section by section, behind the tunneling machine as the latter advances. Those tunneling machines which are designed for use in such relatively soft formations, or both relatively hard and soft formations, are generally equipped with an outer cylindrical casing or shell which forms part of the machine frame and serves to support the tunnel wall in the region between the cutting wheel and tunnel liner, as well as to shield the operating personnel of the machine against falling rock and other debris. The rear end of this shell defines a tail shield within which the additional sections of tunnel liner are assembled and secured to the leading end of the previously installed liner, following each feed stroke of the machine.

The existing tunneling machines have certain inherent deficiencies which this invention seeks to overcome. One of these deficiencies resides in the manner in which driving power or torque is transmitted to the rotary cutting wheel. Thus, in most if not all existing tunneling machines, the rotary cutting wheel is attached to the front end of a relatively long shaft which is rotatably supported in a number of axially spaced bearings on the machine frame. Driving power for the cutting wheel is furnished by several drive motors, typically hydraulic motors, which are mounted on the frame at the rear end of this shaft and are geared or otherwise drivably coupled to the shaft. This drive arrangement has several drawbacks. In the first place, the cutting wheel shaft is generally quite long and driving torque is transmitted through the entire length of the shaft, from the drive motors at the rear end of the shaft to the cutting wheel at the front end of the shaft. As a consequence, the shaft must be made relatively large in diameter to enable the shaft to sustain, without excessive torsional strain or twisting, the large driving torques involved in tunneling operations. Such a large cutter shaft, of course, requires correspondingly large shaft bearings. A large cutter shaft of this kind, and its requisite shaft bearings, are very costly and, in addition, are extremely difficult to initially install as well as to subsequently service, repair, and replace, when necessary, particularly within the confines of a tunnel. Another serious drawback of this type of cutter drive arrangement resides in the fact that the overall torque train for transmitting driving torque to the cutting wheel, i.e., the cutter shaft, shaft bearings, bearing supports, drive motors, and power transmission between the motors and shaft, is quite bulky and results in a relatively massive tunneling machine of large overall size which is extremely difficult and time consuming to install in and remove from a tunnel bore. Also, of course, a torque train of this type embodies a great number of movable precision parts in addition to the cutter shaft and bearings which add to the overall machine cost and render the machine prone to failure or other malfunctioning. A further serious drawback of the existing cutter drive arrangements is that the torque train embodied therein, with its long torque shaft and many moving parts, consumes substantial power owing to friction and other losses. As a consequence, the existing tunneling machines are relatively inefficient and require large drive motors to provide the necessary driving torque at the cutting wheel.

One important aspect of the present invention is concerned with avoiding the above noted deficiencies of the existing tunneling machines. According to this aspect of the invention, the rotary cutting head or wheel of the existing machines is replaced by oscillatory cutter means having forward cutting head means which mount the cutting teeth or other cutting elements. The cutting means are driven in oscillation by linear actuators, such as

hydraulic cutter actuating rams, which are operatively connected directly between the cutting head means and the machine frame. As a consequence, driving torque is transmitted directly to the cutting head means, thus eliminating the need for a massive cutter shaft for transmitting cutter driving torque. This relatively simple, direct drive torque train of the invention obviously achieves a substantial reduction in the overall size, complexity, and cost of the tunneling machine, number of moving parts and power loss in the torque train, and renders the torque train, and hence the overall machine, less prone to failure or other malfunctioning. Moreover, the direct drive torque train of the invention is much easier to service, repair, and replace, when necessary, particularly within the confines of a tunnel. Another advantage of the present invention resides in the fact that it permits removal of the entire cutting mechanism, including the oscillatory cutter means, torque train, and the necessary supporting structure therefor, from the outer shell of the tunneling machine, thereby to adapt the machine to tunneling through relatively soft or fluent formations, such as sand, mud, and the like, by driving the shell only forwardly through the formation in such a way as to shear the tunnel wall, in the manner hereinafter explained.

Another outstanding deficiency of the existing tunneling machines is observed when these machines encounter a non-homogeneous earth formation. As noted earlier, such a non-homogeneous formation is one which presents a tunnel face composed, in part, of relatively hard material, such as rock, and, in part, of relatively soft material, such as sand. In these cases, the rotating cutting wheel of the existing tunneling machines continues to work both the hard and soft portions of the tunnel face equally, with the result that material from the soft face portion is either removed at an excessive rate, or the latter face portion collapses, thereby overloading the machine. The existing tunneling machines are also deficient owing to the relatively inefficient and costly manner in which these machines induce drift, either to counteract an opposing drift tendency created by the surrounding earth formation or to change the direction of the tunnel.

According to a further important aspect of the present invention, the defects, just discussed, of the existing tunneling machines are cured by equipping the present tunneling machine with a number of separate cutters which may be selectively operated either independently or in unison at variable speeds. These several cutters have cutting heads which together sweep a total or combined effective cutting area having a frontal projection, parallel to the longitudinal axis of the machine, which at least approximates the frontal area of the machine, thus to enable the cutters to produce a tunnel bore large enough to pass the tunneling machine. The several cutters sweep different portions of this total effective cutting area. Accordingly, when a non-homogeneous tunnel face formation is encountered, the cutter or cutters which work the hard portion of the face formation may be operated at optimum speed, while the remaining cutters which work the soft portion of the face formation may be operated at reduced speed, or stopped entirely, as necessary to achieve optimum or generally uniform removal of material over the entire area of the tunnel face. Moreover, the oscillatory cutting heads mount gauge cutters which are radially adjustable to induce drift of the tunneling machine in a preselected direction, either to counteract an opposing drift tendency induced by the surrounding earth formation or to change the tunnel direction, in such a way as to avoid the high costs and other disadvantages attendant to drift control in the existing tunneling machines.

The existing tunneling machines have still a further deficiency with which the present invention is concerned. This latter deficiency appears when the tunneling machines encounter sandy or other relatively soft or fluent formations and results from the fact that the plane of rotation of the cutting head or wheel of the existing tun-

neling machines is normal to the longitudinal axis of the machines. As a consequence, the cutting heads tend to cut a tunnel face which is generally vertical. While such a vertical tunnel face is satisfactory in rock and other relatively hard formations, it is quite unsatisfactory in sandy and other relatively soft or fluent formations which possess insufficient shear strength to prevent their collapse. As a consequence, when the existing machines tunnel through these latter formations, breast boards, or the like, must be installed at the tunnel face to reinforce the latter against collapse and the tunnel face is worked by hand or with the aid of a so-called up-and-over tractor shovel, or the like. The rate of advance of the tunnel is thus materially reduced, and the task of driving the tunnel becomes substantially more laborious and hazardous.

A further aspect of the present invention is concerned with this problem of tunneling through relatively soft formations. According to this aspect, the invention provides a tunneling machine in which the cutting plane of the cutter means is inclined at an acute angle relative to the longitudinal axis of the machine in such a way that this plane slopes forwardly in the upward direction. As a consequence, the cutter means are disposed to cut an inclined tunnel face which slopes toward the tunnel bore in the direction of the base of the tunnel face, whereby collapse of the face is inhibited. According to the preferred practice of the invention, for example, the cutting plane of the cutter means is inclined at an angle on the order of 10-30° from the vertical, thereby to cut a tunnel face at the optimum angle of repose for sandy and other relatively soft formations.

A further unique feature of this form of the invention resides in the fact that the tunneling machine is equipped with an outer casing or shell having a leading edge which may be disposed in a plane parallel to the cutting plane of the cutter means to provide the shell with a front overhang which supports the portion of the tunnel crown located directly over the inclined tunnel face. This leading edge of the shell is beveled or sharpened to form an earth shearing edge which may be employed to shear the tunnel wall when the shell is driven forwardly through the formation. In this regard, the present tunneling machine is uniquely arranged to permit removal of the cutter means and the cutter drive torque train from the shell, and the substitution therefor of breast boards, thereby to adapt the machine for tunneling through sandy and other extremely soft formations by driving the essentially empty shell forwardly through the formation.

At this point, therefore, it is apparent that the present invention contributes several unique and highly important improvements to the tunneling art. It is further apparent that a tunneling machine according to the invention may embody, to considerable advantage, any one or more of these improvements. For example, a number of tunneling machines according to the invention are hereinafter described, certain of which embody the oscillatory cutter and direct cutter drive features of the invention. In these machines, the oscillatory cutters have a common axis of oscillation which coincides approximately with the longitudinal axis of the machine and a cutting plane which is normal to this axis. The cutters are oscillated in unison in opposite directions in such a way as to minimize or eliminate reaction torque on the machine frame. Restraint of these tunneling machines against turning in the tunnel bore is thus greatly simplified. Another unique feature of these illustrative tunneling machines resides in the fact that the cutting teeth or cutting elements on the oscillatory cutters are designed to effect a cutting action in both directions of oscillation of the cutters.

There is also hereinafter disclosed a preferred form of the present tunneling machine which embodies all of the several features of the invention heretofore discussed. Thus, this preferred tunneling machine of the invention has multiple oscillatory cutters whose plane of oscillation is inclined relative to the longitudinal axis of the

machine. The oscillation axes of these cutters are vertically offset in such a way that the cutting heads together sweep a generally elliptical total effective cutting area conforming approximately to the elliptical cross section of the outer casing or shell of the tunneling machine in a plane parallel to the inclined cutting plane, or plane of oscillation, of the cutters. This generally elliptical cutting area has a substantially circular frontal projection approximating the frontal area of the shell, whereby the oscillatory cutters are effective to produce a tunnel bore large enough to pass the shell. Another feature of the preferred machine resides in the fact that the cutter structure, and its drive train, are removable from the shell to adapt the machine for tunneling through extremely soft formations by driving the empty shell forwardly with a shearing action through the formation, and the machine frame is equipped with means for installing a breast board across the interior of the empty shell to control the entrance of debris to the interior of the shell.

It is a general object of the present invention, therefore, to provide a new and improved tunneling machine of the character described.

Other objects of the invention are concerned with providing a tunneling machine which is relatively simple in construction, compact in size, economical to fabricate, has relatively few moving parts, is relatively immune to failure, breakdown, and other forms of malfunction, has relatively high operating efficiency, is reliable in operation, and otherwise ideally suited to its intended purposes.

Still other objects, advantages, and features of the invention will become readily evident as the description proceeds.

With these and such other objects in view, the invention consists in the construction, arrangement, and combination of the various parts of the invention, whereby the objects contemplated are attained, as hereinafter set forth, pointed out in the appended claims, and illustrated in the accompanying drawings.

In these drawings:

FIGURE 35 is an enlarged section taken on line 35-35 in FIGURE 34; and

FIGURE 36 illustrates an additional gauge cutter adjustment.

Referring now to these drawings, and particularly to FIGURES 1 through 6, the tunneling machine 10 of the invention which has been selected for illustration therein, will be seen to comprise, in general terms, a frame 12 mounting cutter means 14, means 16 for driving the cutter means in their cutting motion, feed means 18 for

55 feeding the cutter means forwardly against the tunnel face, and conveyor means 20 for disposing of the debris produced by the cutting action of the cutter means. Frame 12 includes an outer cylindrical casing or shell 22 for supporting the tunnel wall in the region directly behind the

60 cutting plane of the cutter means 14 and shielding the operating personnel of the machine against falling rock and other debris. In the particular tunneling machine under discussion, the cutting plane of the cutter means 14 is located forwardly of the front end of the frame shell

65 22 and the effective cutting diameter of the cutter means equals or slightly exceeds the diameter of the shell.

In this particular tunneling machine, the cutter means 14 comprise a pair of separate oscillatory cutters 24 and 26 having a common axis of oscillation which approximately coincides with the longitudinal axis of the frame shell 22. The cutter drive means 16 comprise linear actuating means 28 and 30 which extend laterally of the oscillation axis of the cutters 24, 26 and act between these cutters, respectively, and the machine frame 12 70 in such a way as to drive the cutters in oscillation about

the axis. The illustrated cutter actuating means are hydraulic rams which are powered and controlled by a hydraulic system, diagrammatically indicated at 32. This hydraulic system includes a motor driven hydraulic pump and valve means for selectively pressurizing the cutter actuating rams 28, 30 with hydraulic fluid from the pump and venting the rams in such a way as to cause reciprocating motion of the rams and, thereby, oscillating motion of the cutters.

The cutter feed means 18 comprise a number of hydraulic push rams 34 which extend axially of and secured to the inner surface of the frame shell 22, at positions spaced circumferentially thereabout. These push rams are adapted to react against the front end of the tunnel liner 35 which is installed, section by section, behind the tunneling machine as the latter advances. Extension of the push rams 34 is effective to drive the entire machine structure, including the frame 12 and cutter means 14, forwardly as a unit.

Conveyor means 20 comprise a screw conveyor 36 which is mounted within the bottom of the frame shell 22, adjacent the front end of the shell, and a belt conveyor 38 which is mounted within the shell, rearwardly of the screw conveyor. These conveyors are arranged in such a way that the screw conveyor 36 receives debris D directly from the cutter means 14 and discharges this debris onto the belt conveyor 38. The belt conveyor transports the debris rearwardly through and beyond the rear end of the frame shell 22 and discharges the debris into a waiting dump car C, or the like. The debris is then transported from the working area in this dump car.

Briefly, in operation of the tunneling machine 10, the cutters 24, 26 are driven in oscillation by the hydraulic cutter actuating means 28, 30. The push rams 34 are periodically extended to feed the oscillating cutters forwardly in a cutting stroke against the tunnel face, thus to effect a cutting action of the cutters against the face. The debris removed by the cutters is continuously transported rearwardly through the frame shell 22, by the conveyors 36, 38, to the dump car C. After the push rams 34 have been extended to the limit of their stroke, these rams are retracted and a new section of the tunnel liner 35 is assembled at the front end of the previously installed liner. The procedure is then repeated to again drive the tunneling machine forwardly in a cutting stroke, after which the next section of tunnel liner is added. This procedure of periodically extending the push rams 34 to drive the tunneling machine forwardly in a cutting stroke, retracting the push rams, and adding a new section of tunnel liner is repeated until the tunnel has been driven the desired distance.

Referring now in greater detail to the tunneling machine 10, the machine frame 12 comprises, in addition to the outer shell 22, an inner shell 40. The inner shell is supported in the outer shell 22 by means of three sets 42 of rollers 44. The roller sets 42 each contain a pair of rollers 44 and are spaced 120° apart about the inner shell. Rollers 44 are rotatably mounted in roller brackets 46 bolted to the inner shell 40 and engaged in grooved tracks 48 which extend axially of and are welded or otherwise rigidly secure to the inner surface of the outer shell 22. As will be explained presently, the entire cutting mechanism of the machine, including the cutter means 14 and the cutter drive means 16, is supported by the inner shell 40. The rollers 44 and tracks 48, in turn, support the inner shell, and its continued cutting mechanism, for movement rearwardly from the outer shell 22. As will appear presently, the inner shell and cutting mechanism are thus removed from the machine under certain tunneling conditions. During normal operations of the tunneling machine 10, however, the inner shell 40 is rigidly fixed to the outer shell 22. To this end, the inner shell is fastened to the outer shell by means of bolts 50 which extend through the roller brackets 46 and are threaded in the outer shell, as shown.

Reference is now made to FIGURE 6 which best illustrates the cutters 24 and 26. Cutter 24 comprises a cutting head 52 including a tubular hub 54 and pairs of front and rear arms 56, 58, respectively, which are rigidly secured at their inner ends to and extend radially out from the hub to form cutter spokes. The front and rear arms of each spoke converge in the direction of, and contact at, their outer extremities. The outer contacting ends of these arms are welded or otherwise rigidly joined, as shown. It is significant to note here that the front arms 56 are disposed in a common conical plane generated about the axis of the cutting head hub 54. The rear arms 58 are located in a common flat plane normal to this axis. Extending between and welded or otherwise rigidly joined to the outer extremities of the front arms 56 is a circularly curved cutter faceplate 60. A circularly curved bearing plate 62 extends between and is rigidly joined to the rear arms 58 adjacent their outer ends. The cutter face and bearing plates 60, 62 are centered on the axis of the cutting head hub 54. The spokes defined by the pairs of front and rear arms 56, 58 are spaced 90° apart and the plates 60, 62 are 90° in angular extent. Accordingly, the cutting head 52 has a generally quadrantal shape. Mounted on the front sides of the front cutting head arms 56 and the front side of the cutter faceplate 60 are a number of cutting elements 63. The illustrated cutting elements comprise so-called drag bits and will be explained in greater detail shortly. Rigidly secured to the outer surface of and extending rearwardly from the cutting head hub 54 is a laterally curved torque plate 64. Spaced 90° apart about the axis of the hub 54 are a pair of crank pins 66, 68 which extend parallel to and are spaced along the latter axis. Crank pin 68 is supported at its ends by one of the rear spoke arms 58 of the cutter head 52 and a radial crank arm 70 rigid on the torque plate 64. Crank pin 68 is supported at its ends by a pair of radial crank arms 72 rigid on the torque plate.

Cutter 26 comprises a forward, quadrantal shaped cutting head 74 which is substantially identical in construction to the cutting head 52 except that the tubular hub 54 of the latter cutting head is replaced, in the cutting head 74, of a shaft 76. Spaced 90° apart about the rear end of this shaft are a pair of crank pins 78 and 80 which extend parallel to and are spaced along the shaft axis. These crank pins are supported by radial crank arms 82 and 84, respectively, rigid on the rear end of the shaft 76.

The tubular hub 54 of the cutter 24 comprises a bearing or bushing which is axially bored to rotatably receive the shaft 76 of the cutter 26. The cutter bushing 54 is axially dimensioned to fit on the cutter shaft 76 between the front and rear spoke arms 56, 58 of the cutter head 74.

Within the inner shell 40 of the tunneling machine frame 12 are supporting means 86 for rotatably supporting the cutters 24, 26 for oscillation about their common axis of oscillation. Cutter supporting means 86 comprise a long tubular bearing 88 which is centered on the common axis of the frame shells 22, 40 and extends axially of these shells from a position substantially flush with the front end of the inner shell 40 to a position some distance forwardly of the rear end of this shell. Bearing 88 is supported in the inner shell 40 by means of three sets 90 of radial supporting struts 92. The strut sets 65 each contain a pair of the struts 92 and are spaced 120° apart about the cutter shaft bearing 88. The supporting struts 92 extend radially between the shaft bearing 88 and the roller brackets 46, respectively. Each strut is telescopically adjustable and includes a radially inner sleeve 94 and a radially outer shaft 96 which slides in the sleeve. The inner end of each strut sleeve 94 is rigidly joined to the shaft bearing 88. The radially outer end of each strut shaft 96 is bolted to the adjacent roller bracket 46. The supporting struts 92 are telescopically adjustable to permit eccentric displacement of the cutter shaft bearing 88

from the common axis of the frame shells 22, 40 for the reasons hereinafter explained. In normal operation of the tunneling machine, however, the struts are adjusted to center the shaft bearing on the shell axis. Supporting struts 92 may be releasably secured in adjusted position in any convenient way. The illustrated struts, for example, have bores extending laterally through their respective sleeves and shafts which may be selectively aligned to receive pins, or the like.

Sleeve bearing 88 rotatably receives the shaft 76 of the cutter 26. It is significant to note here that when the cutter 26 is rotatably supported in the bearing 88, the cutter head 74 is situated beyond the front end of the bearing and the rear end of the cutter shaft 76, and the crank pins 78, 80 thereon, are exposed beyond the rear end of the bearing. This may be best observed in FIGURE 1 of the drawings. The tubular hub or bushing 54 of the cutter 24 is rotatably supported on the front end of the cutter shaft 76, between the spoke arms 56, 58 of the cutter head 74.

As noted earlier, the actuating means 28, 30 for driving the cutters 24, 26 in their oscillatory cutting motion comprise hydraulic rams. Thus, the actuating means 28 for cutter 24 comprise a pair of hydraulic rams 98 which are located adjacent the front end of the inner frame shell 40. These rams extend laterally of the longitudinal axis of the machine, as may be best observed in FIGURE 2. Each ram 98 has a cylinder 100 containing a ram plunger 102. The outer ends of the ram cylinders 100 are pivotally attached to the wall of the inner frame shell 40 in the manner shown in FIGURE 2. The outer ends of the ram plungers 102 are pivotally secured to the crank pins 66, 68, respectively, on the cutter 24. As may be observed in FIGURE 2, the rams 98 are arranged in such a way that extension of one ram drives the cutter 24 in one direction of oscillation and extension of the other ram drives this cutter in the opposite direction of oscillation. Accordingly, the two rams 98 may be alternately pressurized to drive the cutter 24 in its oscillatory cutting motion. In actual practice, the rams 98 may be either single acting or double acting. Preferably, however, double acting rams are employed in the machine so that each ram delivers a driving torque to the cutter 24 during both extension and retraction of the ram.

Similarly, the actuating means 30 for the oscillatory cutter 26 comprise a pair of hydraulic rams 104 including cylinders 106 and plungers 108 movable in the cylinders. Rams 104, like the actuating rams 98 for the cutter 24, extend transversely of the machine axis. The outer ends of the ram cylinders 106 are pivotally attached to the frame shell 22. The outer ends of the ram plungers 108 are pivotally attached to the crank pins 78, 80 on the cutter 26. Rams 104, like the rams 98, are preferably double acting and are thus effective to drive the cutter 26 in its oscillatory motion in response to alternate pressurizing of the ends of the ram cylinders 106.

It is evident at this point, therefore, that the cutter actuating means 28, 30 are effective to drive the cutters 24, 26 in an oscillatory cutting motion about their common axis of rotation. As noted earlier, these actuating means are hydraulically powered by the hydraulic control system 32 which includes valves (not shown) for controlling hydraulic fluid flow to and from the cutter actuating rams 98, 104 in such a way as to oscillate the cutters. In the particular tunneling machine under discussion, the cutters 24, 26 are intended to oscillate in unison but in opposite directions in such manner that the cutting torque on each cutter substantially balances or neutralizes the cutting torque on the other cutter, thus to minimize or eliminate reaction torque on the tunneling machine frame 12. If desired, however, the hydraulic system 32 for the cutter actuating rams may be designed to permit selective or independent oscillation

of the cutters in the same manner as the cutters of a later described embodiment of the invention.

It is significant to note at this point that the two oscillatory cutters 24, 26 together sweep a total effective cutting area having a frontal projection parallel to the central axis of the tunneling machine which at least approximates the major transverse cross section of the machine frame 12, that is the frontal area of the frame shell 22. Accordingly, the cutters are effective to cut a tunnel bore large enough to pass the tunneling machine. It is further significant to note that the two cutters sweep different portions of this total effective cutting area. In this regard, it will be observed that each cutter 24, 26 oscillates through an angle of approximately 90° between a first limiting position illustrated in FIGURE 2 and a second limiting position illustrated in FIGURE 5. Accordingly, cutters 24, 26 sweep the upper half and the lower half, respectively, of the total effective cutting area of the cutters. It is also significant to note that in the limiting positions of the cutters, the radial sides of the cutters are disposed in close proximity or abut, whereby the cutters together sweep substantially the entire frontal area of the frame shell 22.

As noted earlier, the cutting elements 63 on the cutters 24, 26 comprise so-called drag bits or teeth. Each drag bit is disposed at an acute angle relative to a radial plane of its respective cutter which intersects the bit, as shown best in FIGURES 2 and 6, whereby the drag bits are effective to exert a cutting action in both directions of oscillation of the cutters. It should be understood, of course, that the illustrated drag bits are intended to be purely illustrative in nature and that other types of cutting elements may be employed on the oscillatory cutters 24, 26.

It will be recalled that the feed means 18 for periodically driving or feeding the oscillating cutters 24, 26 forwardly into cutting engagement with the tunnel face comprise a number of hydraulic push rams 34. These push rams extend axially of the tunneling machine and include ram cylinders 110 which are welded or otherwise rigidly secured to the inner wall of the frame shell 22, at positions uniformly spaced about the shell. Movable within each ram cylinder 110 is a plunger 112 which extends rearwardly from the cylinder. Thrust shoes 114 are mounted on the rear ends of the push ram plungers 112 for thrusting engagement with the leading end of the tunnel liner 35. During operation of the tunneling machine, the ram plungers 112 are periodically extended to drive the machine frame 12 and the oscillating cutters 24, 26 to forwardly in unison, in the manner discussed earlier, thereby to feed the cutters forwardly against the tunnel face.

This feeding of the oscillating cutters 24, 26 forwardly into cutting engagement with the tunnel face produces a rearward reaction thrust on the cutters. The cutters are axially supported against rearward displacement under the force of this reaction thrust by thrust bearing rollers 116. Thrust rollers 116 are rotatably mounted in brackets 117 which are welded or otherwise rigidly secured within the front end of the inner frame shell 40 at positions uniformly spaced about the later shell. Thrust rollers 116 seat against the rear bearing plates 62 on the cutter heads 52, 74, thus to support the cutters 24, 26 in the axial direction. The circumferential space between the adjacent thrust rollers 116 is such that each cutter 24, 26 is axially supported at all times by a number, typically three of the thrust rollers.

The screw conveyor means 36 comprise a pair of rotary augers 118 which are disposed side by side within an inclined conveyor trough 120 mounted on the inner frame shell 40. This trough slopes upwardly in the direction of its rear end, as shown best in FIGURE 1, and is disposed within a bottom cutout in the front end of the inner shell. The conveyor augers 118 are rotatably supported at their ends in bearings 122, 124 mounted on the

ends of the conveyor trough. Hydraulic motors (not shown) are provided for driving the augers 118 in opposite directions of rotation in such manner that the augers are effective to feed or convey debris upwardly through the conveyor trough 120. In this regard, it will be observed that the lower end of the conveyor trough 120 opens to the bottom interior of the outer frame shell 22, directly behind the cutter heads 52, 74, whereby debris from the cutter is adapted to enter the lower end of the trough.

The upper end of the screw conveyor trough 120 overlies the lower end of the belt conveyor 38 which is disposed within a cutout in the bottom of the inner frame shell 40. This belt conveyor slopes upwardly in the direction of its rear end and comprises an endless conveyor belt 126 driven by a hydraulic motor (not shown). The upper run of the conveyor belt 126 travels upwardly in FIGURE 1. It is evident at this point, therefore, that the screw conveyor 36 is effective to discharge cutting debris D onto the lower end of the belt conveyor 38 and that this debris is then transported upwardly by the latter conveyor and finally discharged into the hopper car C.

During operation of the tunneling machine, the debris produced by the cutting action of the oscillating cutters 24, 26 passes rearwardly through and about the cutters into the front end of the inner frame shell 40. Mounted within the bottom half of this inner shell, adjacent the front end of this shell, are a number of baffles 128 for deflecting or directing the entering debris inwardly toward the auger conveyor trough 120. Extending outwardly from the upper edges of the trough sidewalls to the wall of the inner shell 40 are partitions 130 on which the debris dropping from the baffles 128 collects and from which this debris passes to the conveyor augers 118.

As noted earlier, the push rams 34 and the drive motors for the conveyor augers 118 and the conveyor belt 126 are hydraulically powered. The hydraulic system 32 of the tunneling machine may be equipped with means for controlling the push rams and conveyor drive motors as well as the cutter actuating rams 98, 104.

The operation of the tunneling machine 10 is believed to be obvious from the preceding description. Thus, during operation of the machine, the cutter actuating rams 98, 104 are powered to drive the cutters 24, 26 in their oscillatory cutting motion and the push rams 34 are extended to drive the oscillating cutters, and the machine frame 12, forwardly in unison in a cutting stroke. During this cutting stroke, the oscillating cutting heads 52, 74 of the cutters are urged or fed into cutting engagement with the tunnel face. The debris removed by the oscillating cutter passes rearwardly into the front end of the inner frame shell 40 and is then conveyed rearwardly through the machine to the hopper car C by the screw conveyor 36 and the belt conveyor 38. As noted earlier, the push rams 34 are effective to produce forward driving thrust on the tunneling machine by virtue of the thrusting engagement of the push ram thrust shoes 114 with the leading end of the tunnel line 35. After the push rams 34 have been extended to the limit of their stroke, the rams are retracted, and a new section of tunnel liner is installed within the rear end portion or tail shield of the tunneling machine frame shell 22. Thereafter, the push rams are again extended to drive the machine frame 12 and the oscillating cutters 24, 26 forwardly in unison in a cutting stroke. This procedure is repeated until the tunnel has been driven the desired distance. As noted earlier, the cutters 24, 26 of the illustrated cutting machine are intended to be operated in such manner that these cutters oscillate in unison but in opposite directions, thus to minimize reaction torque on the machine frame. If desired, however, the hydraulic system 32 of the machine may be designed to permit selective or independent control or operation of the cutters for the beneficial reasons hereinafter explained in connection with the later embodiment of the invention.

It will be recalled that the inner frame shell 40 is movably supported, by means of the rollers 44, within the outer frame shell 22 and is normally retained in a fixed position within the latter shell by the anchor bolts 50. When tunneling through extremely soft earth formations, such as sand, it is often desirable to terminate operation of the oscillatory cutters 24, 26, install a transverse bulkhead or breast board within the leading end of the frame shell 22, and continue tunneling by merely driving the shell forwardly through the formation. This necessitates removal from the frame shell 22 of the cutters, the cutter supporting and driving means, and the conveyors. This is accomplished by releasing the cutting heads 52, 74 from the cutter shaft 76, releasing the supporting structure for the belt conveyor 38 from the outer frame shell 22, removing the anchor bolts 50 from the inner frame shell 40, and retracting the latter frame shell rearwardly from the outer frame shell. The cutting heads are then removed rearwardly through the outer shell. Thereafter, the breast board (not shown) is installed within and just behind the front end of the outer frame shell. Finally, the push rams 34 are alternately extended and retracted, in a manner similar to that explained above, to periodically drive the outer shell forwardly through the soft earth formation. The breast board is equipped with an opening through which debris is removed from the tunnel face, either by hand or with the aid of an up-and-over earth handling machine.

Occasionally, it is desirable or necessary to alter the direction of forward movement of the tunneling machine as the latter progresses through an earth formation. The lateral or radial cutter adjustment afforded by the adjustable, telescoping struts 92 permit such direction control. Thus, when it is desired to turn the tunneling machine in any direction, the cutter bearing supporting struts 92 are adjusted to laterally offset the cutters 24, 26 in that direction, thus to cause the machine to follow an arcuate path which curves in the corresponding direction.

In the tunneling machine 10 described above, the oscillatory cutters 24, 26 together have an effective cutting diameter which is substantially equal to or slightly greater than the diameter of the outer frame shell 22. Accordingly, the cutters cut both the face and wall of the tunnel. This cutter arrangement is suitable for tunneling through relatively hard and medium hard formations. When tunneling through relatively soft earth formations, on the other hand, it is often desirable to utilize the oscillatory cutters 24, 26 for cutting the tunnel face only and to utilize the front end of the outer frame shell 22 as a shearing edge for shearing the tunnel wall. FIGURE 7 illustrates a modified tunneling machine 10a according to the invention which is designed to effect this latter method of tunneling. The tunneling machine 10a is identical to the tunneling machine 10 described above except that the effective overall cutting diameter of the oscillatory cutters 24a, 26a is slightly less than the internal diameter of the outer frame shell 22. Also, the cutting heads 52a, 74a are retracted rearwardly to a position within the leading end of the outer frame shell, as illustrated. This rearward retraction of the cutting heads to their cutting positions within the outer frame shell is accomplished by removing the anchor bolts 50 which secure the inner frame shell 40 to the outer frame shell 22 and rolling the inner frame shell, together with the cutter and conveyor structure supported thereon, rearwardly in the outer frame shell to the position illustrated in FIGURE 7. The inner frame shell is then re-anchored to the outer frame shell. The belt conveyor 38 is adjusted rearwardly with the inner frame shell 40.

The modified tunneling machine 10a operates in much the same manner as the earlier tunneling machine of the invention. However, during operation of the tunneling machine 10a, the oscillating cutters 24a, 26a cut only the tunnel face. The tunnel wall is sheared by the leading edge of the outer frame shell 22 during each forward,

unified cutting stroke of the oscillating cutters and the machine frame 10. If desired, the leading edge of the outer frame shell 22 may be beveled or sharpened to define a relatively sharp earth shearing edge capable of efficiently shearing the wall or the tunnel.

Reference is now made to FIGURES 8 through 11 which illustrate a further modified tunneling machine 200 according to the invention. This modified tunneling machine is similar to the earlier tunneling machines of the invention in that the modified machine has a frame 202 including an outer frame shell 204, an inner frame shell 206, and interengaging roller and track means 208 on these shells for coaxially supporting the inner shell within the outer shell. Anchor bolts 210 are provided for releasably anchoring the inner shell relative to the outer shell, as before.

Coaxially disposed relative to the frame shells 204, 206 are a pair of oscillatory cutters 212, 214. Cutter 212 has a shaft 215 mounting a forward cutting head 216. Cutting head 216 is circular in frontal elevation, except for a V-shaped cut-out 218 which extends from a point adjacent the center of the head outwardly through the edge of the head. Cutter 214 has a cutting head 220 including a generally circular backplate 222 and a radially outer ring 224 which projects forwardly from the back-plate into surrounding relation with the cutting head 216. At the center of the cutting head backplate 222 is a hub 226 which is axially bored to receive a bushing 228. Bushing 228 is bolted to the plate 222, as shown, and is rotatably supported on the cutter shaft 215, directly behind the cutting head 216. Cutting head 220 has a V-shaped cut-out 230 matching the cut-out 218 in the cutting head 216. As shown best in FIGURE 9, the front face of the cutting head 216 and the front face of the outer ring 224 of the cutting head 220 conform to a common conical surface generated about the common axis of the cutters 212, 214.

The shaft 215 of cutter 212 is rotatable in a bushing 232 which extends axially through the inner frame shell 206. Bushing 232 is supported within the inner shell by telescoping struts 234. These struts extend radially between and are secured at their ends to the bushing and the mounting brackets 236 for the inner shell supporting rollers 208. Supporting struts 234, like the bushing supporting struts in the earlier embodiments of the invention, are telescopically adjustable to center the bushing 232 on or displace the bushing laterally from the central longitudinal axis of the tunneling machine, that is the common axis of the frame shells 204, 206. However, the supporting struts 234 in the tunneling machine under consideration comprise hydraulic rams including radially inner ram cylinders 238 which are secured to the bushing 232 and radially outer ram plungers 240 which are secured to the roller brackets 236. It is evident at this point that the bushing 232 may be selectively positioned on or eccentric to the longitudinal axis of the tunneling machine by selective pressurizing of the hydraulic struts 234.

Tunneling machine 200 is equipped with actuating means 242 for driving the cutters 212, 214 in oscillation. As in the previous embodiments of the invention, the cutters are intended to oscillate in unison but in opposite directions in such a way as to minimize or eliminate reaction torque on the machine frame 202. Conceivably, however, cutters may be operated independently for the reasons hereinafter explained in connection with a later embodiment of the invention. Cutter actuating means 242 comprise a first pair of hydraulic cutter actuating rams 244 for driving the cutter 214. Rams 244 are operatively connected between the inner frame shell 206 and the cutter 214 in essentially the same manner as the cutter actuating rams in the previous embodiments of the inventions. Accordingly, a detailed description of the rams 244 and their mode of attachment to the inner shell 206 and cutter 214 is deemed unnecessary. Suffice it to say that the rams preferably comprise double acting rams having

ram cylinders, the ends of which may be selectively pressurized to drive the cutter 214 in oscillation.

The cutter actuating means 242 include a second pair of hydraulic cutter actuating rams 246 for driving the cutter 212 in oscillation. These rams are drivably coupled to the shaft 215 of the cutter 212 by the ring gear and pinion torque transmission means 248 illustrated in FIGURES 10 and 11. This torque transmission means comprises a pinion 250 which is fixed to the rear end of the cutter shaft 215 and an internal ring gear 252 which meshes, at one position, with the pinion 250. Ring gear 252 is rotatably supported, on an axis eccentric to the axis of the cutter shaft 215, by a sector shaped bracket 254 which is bolted to the cutter shaft bushing 232. This bracket mounts a pair of bearing pins 256 which engage slidably within a curved coaxial guideway or slot 258 in one side face of the ring gear 252 and a curved bearing flange 260 opposite the bearing pins for retaining the ring gear in supporting relation to the pins. It is evident at this point that the bracket 254, including its bearing pins 256 and bearing flange 260, provide an effective ring gear bearing which rotatably supports the ring gear 252 for turning on its central axis. It is further evident that rotation of the ring gear 252 drives the pinion 250, and thereby the cutter 212, in rotation.

Cutter actuating rams 246 extend laterally of the longitudinal axis of the tunneling machine and include cylinders 262 and plungers 264. The outer ends of the ram cylinders 262 are pivotally secured to the inner frame shell 206. The outer ends of the ram plungers 264 are pivotally attached to the ring gear 252 at positions spaced circumferentially thereabout. As shown in FIGURES 10 and 11, the cutter actuating rams 246 are arranged in such a way that these rams are effective to drive the ring gear 252, and thereby the cutter 212, in oscillation in response to alternate pressurizing of the ends of the ram cylinders.

In lieu of the drag bits embodied in the earlier tunneling machines of the invention, the cutters 212, 214 of the tunneling machine 200 under discussion mount a number of conventional conical rolling cutters 266. These rolling cutters are distributed over the front conical faces of the cutting heads 216, 220 in the manner illustrated best in FIGURE 8. In addition, the cutter 212 mounts a central pilot bit 267 which is located at the forward end of the cutter shaft 215 and includes three conical rolling cutters 268 arranged in the triangular pattern shown in FIGURE 8.

As in the previous embodiments of the invention, the tunneling machine 200 is equipped with a number of hydraulic push rams 270 for periodically driving the tunneling machine frame 202 and the oscillating cutters 212, 214 forwardly in unison. These cutter actuating rams are mounted on the inner wall of the outer frame shell 204. During each forward feed stroke of the machine, the cutters 212, 214 are fed forwardly into cutting engagement with the tunnel face, thus resulting in a rearward axial thrust on the cutters. The cutters are axially supported against rearward displacement under the action of this cutting thrust by thrust bearings 272 and 274. Thrust bearing 272 surrounds the cutter shaft 215 between the backplate 222 of the cutter 214 and the front end of the cutter shaft bushing 232. Thrust bearing 272, therefore, axially supports the cutter 214. Thrust bearing 274 comprises a number of conical thrust bearing rollers 276 which are contained within a raceway 278 defined by curved coaxial, confronting channels or grooves in the rear side of the cutting head 216 and the front side of the cutting head 220. The axial cutting thrust on the cutter 212, therefore, is transmitted from the latter cutter, through the thrust bearing rollers 274, to the cutter 214 and then from this cutter, through the thrust bearing 272, to the cutter shaft bearing 232.

During operation of the tunneling machine 200, the cutters 212, 214 are driven in oscillation and are peri-

odically fed forwardly against the tunnel face to effect cutting action. The debris removed by the cutters passes rearwardly through the cut-outs or openings 218, 230 in the cutting heads 216, 220 into the interior of the inner frame shell 296. This debris is then removed by conveyor means (not shown). It is obvious that the oscillatory cutter arrangement embodied in the tunneling machine 200 permits greater latitude in the oscillatory angle of the cutters 212, 214 than does the oscillatory cutter arrangement embodied in the earlier forms of the invention. In this regard, the preferred practice of the invention is to obtain the maximum possible amplitude of oscillation of the cutters. It is evident that the oscillatory cutter arrangement under discussion permits such a maximum oscillation amplitude.

It will be understood, of course, that the modified tunneling machine 200 is equipped with a hydraulic system for operating or pressurizing the cutter actuating rams 244, 246, and, as noted earlier, with conveyor means for removing and disposing of the debris produced by the cutting action of the oscillating cutters. The hydraulic system and conveyor means of the tunneling machine 200, however, is substantially identical to those of the earlier embodiments of the invention and, for this reason, have been omitted from the drawings.

Reference is now made to FIGURES 12 through 32 illustrating a preferred oscillating cutter tunneling machine 300 according to the invention which is superior in many respects to the tunneling machines described thus far. Tunneling machine 300 is generally similar to the earlier tunneling machines in that the tunneling machine 300 has a frame 302 including an outer shell 304 and mounting a pair of oscillatory cutters 306 and 308. Within the frame shell 304 are means 310 supporting the cutters 306, 308 for oscillation in a common plane transverse to the longitudinal axis of the tunneling machine, that is the central axis of the frame shell, and cutter actuating means 312 for driving the cutters in their oscillatory cutting motion. Also mounted in the frame shell 304 are feed means 314 for periodically driving the frame 302 and the oscillating cutters 306, 308 forwardly in unison in a cutting stroke, thus to urge or feed the cutters against the tunnel face. The debris produced by the cutting action of the cutters is continuously removed or transported rearwardly through the frame shell 304 by conveyor means 316 mounted within the shell.

The tunneling machine 300 operates in much the same way as the earlier tunneling machines of the invention. Thus, during operation of the machine 300, the cutter actuating means 312 are periodically energized to drive the cutters 306, 308 in their oscillatory cutting motion and the cutter feed means 314 are energized to drive the machine frame 302 and the cutters forwardly in unison in a cutting stroke. The cutters are thereby fed against the tunnel face to effect a cutting action on the face. The debris produced by this cutting action passes rearwardly through the cutters to the conveyor means 316 and is then transported rearwardly through the frame shell 304 by these conveyor means to a waiting dump car, or the like, (not shown). At the conclusion of each forward cutting stroke of the tunneling machine, a new section of tunnel liner 318 is installed within the rear removable tail shield portion of the frame shell 304. The cutter feed means 314 are then again energized to drive the machine frame 302 and the oscillating cutters 306, 308 forwardly in another cutting stroke. This procedure is repeated until the tunnel has been driven the desired distance.

As noted earlier, and hereinafter discussed in detail, the tunneling machine 300 under discussion is superior in many respects to the tunneling machines described earlier. One improved feature of the tunneling machine 300, for example, resides in the fact that the plane of oscillation or the cutting plane of the oscillatory cutters 306, 308 is inclined at an acute angle relative to the lon-

gitudinal axis of the machine in such a way that this plane slopes forwardly from the vertical in the upward direction, as best illustrated in FIGURE 16. This forward slope of the cutters is designed to produce a tunnel face which is inclined at the optimum angle of repose of relatively soft or loose earth materials, such as sand, thus to inhibit collapse of the tunnel face when tunneling through such relatively soft or loose materials. The inclined oscillatory or cutting plane of the cutters in the tunneling machine 300, of course, is in contrast to the earlier tunneling machines of the invention, wherein the oscillatory or cutting plane of the cutters is disposed at right angles to the longitudinal axis of the machine. Another unique feature of the tunneling machine 300 is that the oscillation axes of the cutters 306, 308 are vertically offset in such a way as to provide the cutters with a generally elliptical, total effective cutting area which approximates the elliptical cross section of the frame shell 304 in a plane parallel to the plane of the cutters. This offset arrangement of the cutter axes, therefore, provides the cutters with a total effective cutting area having a generally circular frontal projection, parallel to the longitudinal axis of the machine, which approximates the major frontal area of the frame shell 304. Accordingly, the cutters are disposed to cut a generally circular tunnel bore large enough to pass the machine. Yet another unique feature of the tunneling machine 300 resides in the fact that the front edge of the frame shell 304 is disposed in a plane parallel to the plane of oscillation or cutting plane of the cutters 306, 308. This arrangement provides the frame shell with an upper forward overhanging portion or lip which overlies the sloping tunnel face produced by the cutters and supports the tunnel roof in the region above this sloping face. A particularly important and unique feature of the tunneling machine 300 is that the cutter actuating means 312 are operatively connected to the cutters 306, 308 in such a way as to eliminate the necessity of long cutter shafts, and shaft bearings, which are both costly and introduce undesirable torsional elasticity and friction losses. In this regard, a significant advantage of all of the disclosed forms of the invention involves the fact that the cutters are driven in oscillation by laterally extending hydraulic rams which are directly coupled to the cutters, thereby eliminating the costly and relatively inefficient geared power transmissions commonly employed in the existing tunneling machines.

Referring now in greater detail to the tunneling machine 300, the frame shell 304 is circular in transverse cross section. The front edge of the shell is disposed in a plane inclined in an acute angle to the longitudinal axis of the shell, as just noted and shown in FIGURE 16. Welded or otherwise fixed within the front end of the shell is a reinforcing metal band or ring 322. Welded to the outside of the shell, adjacent its front end, and extending about the upper half of the shell between generally diametrically opposite positions located slightly below the level of the tunnel spring line, is a relatively hard outer metal band 324. The front edges of the metal bands 322, 324 are disposed flush with the front edge of the frame shell 304 and the front shell and band edges are beveled, as shown, to define a forward earth shearing edge 320 on the shell.

Referring to FIGURES 12 through 14, 16, 17, 23 and 24, it will be observed that the oscillatory cutters 306, 308 are substantially identical. Accordingly, a description of one cutter, namely cutter 306, will suffice for both. Cutter 306 has a generally sector shaped cutting head 326 including a cutting head mount or hub 328. Hub 328 has a bushing 330, welded to the ends of which are front and rear plates 332, 334 disposed in parallel planes normal to the bushing axis. These bushing plates have coplanar edges, which appear as left hand, lower, and right hand edges in FIGURE 13, and to which are welded apertured mounting plates 336. Located at the rear end of the hub 328, in a plane normal to the axis of the hub bushing 330,

is a torque plate or arm 338. The inner end of this torque arm is slotted to straddle the rear ends of the mounting plates 336, as shown, and is welded to the outer surfaces of these plates. The outer end of the torque arm 338 has laterally projecting apertured ears 340.

Extending radially from the cutter hub 328, normal to the three hub mounting plates 336, respectively, are three spokes 342. These spokes include front plates 344 which are disposed in a common plane normal to the axis of the hub bushing 330 and tubular reinforcing members 346 welded to the rear surfaces of the plates. A generally triangular scraper blade 347 is welded to the rear side of the center spoke for reasons to be explained. Also welded to the rear surfaces of the spoke plates 344 and to the inner ends of the reinforcing members 346, are apertured mounting plates 348 which extend rearwardly from and are disposed in planes normal to the longitudinal axes of the spokes 342, respectively. The spoke mounting plates 348 seat on the hub mounting plates 336, respectively, in such a way that the holes in the respective seating plates are aligned. The spokes 342 are secured to the hub 328 by bolts which extend through the aligned holes in the respective contacting hub and spoke mounting plates. Extending between and bolted to the adjacent spokes 342 are reinforcing struts 350.

Cutter 306 is completed by a number of cutting elements, or drag bits, 352 which are mounted on the front sides of the cutter spokes 342. These drag bits are designed to effect a cutting action in both directions of oscillation of the cutter 306 and will be described presently.

Cutter 308 is substantially identical to the cutter 306, just described, and differs from the latter cutter only by the omission of the scraper blade 347. Accordingly, a detailed description of the cutter 308 is unnecessary. For convenience in the ensuing description, the elements of cutter 308, which are referred to in the later description, are indicated by the same reference numerals as the corresponding elements of cutter 306.

Cutter mounting means 310 comprise a cutter mounting frame 354 fixed within the frame shell 304. This frame includes an upper horizontal beam 356 and a pair of lower vertical supporting legs 358. The upper horizontal beam 356 is located slightly above the longitudinal center line of the frame shell 304 and includes two outer I-beam sections 360 and an intervening cutter shaft support 362. The outer beam sections 360 have apertured transverse mounting plates 364 at their outer ends. These mounting plates are bolted to beam mounting brackets 366 which are welded or otherwise rigidly secured to the inner wall of the frame shell 304 at the ends of the horizontal beam 356. The inner ends of the horizontal beam sections 360 have apertured transverse mounting plates 368 which are spaced to receive therebetween the cutter shaft support 362. The vertical supporting legs 358 of the cutter mounting frame 354 extend between and are bolted to the horizontal beam sections 360, respectively, and the bottom of the frame shell 304.

The cutter shaft support 362 comprises a rectangular box-like housing 370. The two vertical side walls and the top side wall of this housing comprise apertured side and top mounting plates 372, 374, respectively. Extending through the housing 370, parallel to these mounting plates, and fixed to the front and rear housing walls are a pair of vertically spaced bushings 376. A pair of cutter supporting shafts 378 extend through and are welded or otherwise rigidly secured to the bushings 376. Cutter shafts 378 will be observed to extend a distance beyond the forward ends of the bushings. As shown best in FIGURE 19, the cutter shaft support housing 370 is positioned between the inner ends of the horizontal beam sections 360 in such a way that the holes in the inner mounting plates 368 of these beam sections and the holes in the side mounting plates 372 of the housing are aligned. The cutter shaft support housing is secured to the beam sections by means of bolts which extend through the aligned

holes, as shown. The cutter mounting frame 354 is completed by an upper upright supporting leg 380 which extends between and is bolted to the upper mounting plate 374 of the cutter shaft support housing 370 and the upper wall of the frame shell 304.

It is significant to note at this point that the cutter mounting frame 354 may be disassembled and removed from the frame shell 304. The purpose of this removable construction of the mounting frame will be explained presently. It is further significant to note that the cutter mounting frame 354 is disposed in a plane which parallels the front edge 320 of the frame shell 304 and is thereby inclined at an acute angle relative to the longitudinal axis of the frame shell. The cutter supporting shafts 378 extend normal to the inclined plane of the frame, and therefore normal to the inclined plane of the front frame shell edge 320, and are disposed in a common vertical plane containing the longitudinal axis of the frame shell. As a consequence, the axes of the cutter shafts are disposed at an acute angle to the longitudinal shell axis.

The hub bushing 330 of the lower oscillatory cutter 306 is rotatably fitted on the lower cutter shaft 378. The hub bushing of the upper cutter 308 is rotatably fitted on the upper cutter shaft. Positioned between these hub bushings and the bushings 376 of the cutter shaft support 362 are thrust washers 382. Additional thrust washers 384 are positioned on the cutter shafts 378 forwardly of the cutter hub bushings 330. Bolted to the front ends of the cutter shafts 378 is a retaining plate 386. This retaining plate serves to retain the cutters 306, 308 on their respective cutter shafts.

It is evident at this point that the cutters 306, 308 are rotatably supported on the cutter shafts 378 for oscillation in a common plane of oscillation which parallels the inclined plane of the front edge 320 of the frame shell 304 and is inclined at an acute angle relative to the longitudinal axis of the shell. In contrast to the earlier forms of the invention, the oscillation axes of the cutters 306, 308 do not coincide but are rather vertically offset or displaced. The reason for this vertical displacement of the cutter axes will be explained presently.

The cutter actuating means 312 for driving the cutters 306, 308 in their oscillatory cutting motion comprise a first pair of hydraulic cutter actuating rams 388 for driving the lower cutter 306 and a second pair of hydraulic cutter actuating rams 390 for driving the upper cutter 308. These cutter actuating rams extend laterally of the longitudinal axes of the machine, as in the earlier forms of the invention, and are disposed directly behind the cutting heads 326 of the cutters. The cutter actuating rams 388 for the lower cutter 306 are located at opposite sides of its cutter shaft 378 and include cylinders 392 and plungers 394 extending from the cylinders. The outer ends of the ram cylinders 392 are pivotally attached to ram mounting brackets 396, respectively, which are welded to the inner wall of the frame shell 304 at diametrically opposite sides thereof. The outer ends of the ram plungers 394 are pivotally attached to the apertured ears 340, respectively, of the torque arm 338 on the lower cutter 306. Similarly, the hydraulic actuating rams 390 for the upper cutter 308 comprises cylinders 398 and plungers 400 extending from the cylinders. The outer ends of the ram cylinders 398 are pivotally attached to the ram mounting brackets 396, respectively. The outer ends of the ram plungers 400 are pivotally attached to the apertured ears 340 of the torque arm 338 on the upper cutter 308. As in the earlier forms of the invention, the cutter actuating rams 388, 390 are preferably double acting.

It is evident at this point that the cutters 306, 308 may be driven in their oscillatory cutting motion by selective pressurizing of the cutter actuating rams 388, 390. As mentioned earlier, and hereinafter further discussed, the cutters of the tunneling machine under discussion are capable of independent operation or control. Thus, as will appear from the later description, these cutters may be

selectively operated independently or in unison at selectively variable speeds. As a consequence, the cutters may be operated to oscillate at the same speed in opposite directions, as in the earlier forms of the invention, at the same speed in the same direction, or at different speeds in the same or opposite directions. Moreover, one cutter may be operated while the other cutter remains stationary. Another feature of the tunneling machine under discussion resides in the fact that the cutters 306, 308, and their actuating rams 388, 390, may be removed from the frame shell 304, along with the cutter mounting frame 354, for reasons to be explained presently.

The cutter feed means 314 comprise a number of hydraulic push rams 402 which are circumferentially spaced about the interior of the frame shell 304. Each push ram 402 includes a cylinder 404 and a plunger 406 extending rearwardly from this cylinder. Mounted on the rear ends of ram plungers 406 are thrust shoes 408. In contrast to the earlier forms of the invention, the push rams 402 are removably mounted within the frame shell 304. To this end, a number of hollow, channel shaped ram housings 410, equal to the number of push rams 402, are welded or otherwise rigidly secured to the inner wall of the frame shell 304 at positions spaced circumferentially thereabout. These ram housings extend axially of the shell and are open at their rear ends. The push ram cylinders 404 fit slidably within the ram housings 410 and are releasably secured within their respective housings by removable anchor means 412. The illustrated anchor means 412 comprise anchor pins 414 which extend through aligned transverse bores in the side walls of the ram housings 410 and forward axial tongues 416 on the ram cylinders 404, as may be best observed in FIGURES 21 and 22. The hydraulic hoses for the push rams 402 extend through openings in the ram housings and are releasably secured to the ram cylinders, thus to permit removal of the push rams from the ram housings 410 by pulling the rams rearwardly from the housings.

During operation of the tunneling machine 300, the push rams 402 are periodically extended to drive the machine frame 302 and the oscillating cutters 306, 308 forwardly in unison in a cutting stroke, during which the cutters are urged or fed against the tunnel face to effect the cutting action. The cutters are thereby subjected to a rearward axial reaction thrust. Thrust bearing means 418 are provided for supporting the cutters axially against rearward displacement under the force of this reaction thrust. Referring to FIGURES 13, 14, 16 and 23, the thrust bearing means 418 will be seen to comprise a thrust bearing ring 420 which is disposed behind and parallel to the oscillatory plane of the cutters 306, 308. As may be best observed in FIGURES 13 and 19, the cutter thrust ring 420 is not truly circular in shape. Rather, the thrust ring is elongated in the vertical direction and includes a lower, generally semicircular portion 420a which is centered on the oscillation axis of the lower cutter 306 and an upper, generally semicircular portion 420b which is centered on the oscillation axis of the upper cutter 308. The ends of these lower and upper thrust ring portions are integrally joined by intervening, generally linear ring portions 420c. Bolted to the rear sides of the cutter spokes 342 are brackets 424 mounting thrust rollers 426. The thrust rollers 426 on the lower cutter 306 are disposed to ride on the front face of the lower semicircular thrust ring portion 420a. Similarly, the thrust rollers on the upper cutter 308 are disposed to ride on the front face of the upper semicircular thrust ring portion 420b. Preferably, the thrust rollers 426 comprise conical bearing rollers, as illustrated, mounted with their axes of rotation inclined to the plane of the thrust ring 420 in such a way that the rear sides of the rollers seat flat against the thrust ring.

As best shown in FIGURES 16 and 25, the debris conveyor 316 comprises an endless conveyor belt 428 which encircles and is mounted for endwise movement on a

frame 430. Conveyor 316 slopes upwardly in the rearward direction and has its lower front end disposed adjacent the bottom and front end of the frame shell 304. Welded within and disposed in a plane normal to the frame shell 304, at the front end of the conveyor 316, is a reinforcing ring 432. As shown best in FIGURE 16, the cutter mounting assembly 310 is attached, at its lower end, to the frame shell 304 rearwardly of the ring 432 and in its upper end to the frame shell forwardly of this ring, whereby the assembly extends through the central opening in the ring. The front end of the conveyor 316 is releasably secured to the frame shell 304 in any convenient manner. The rear end of the conveyor is supported in its illustrated elevated position by means of a pair of supporting struts 436. The rear ends of these struts straddle and are secured to opposite sides of the conveyor frame 430. The front ends of the struts are pivotally secured to brackets 438 welded to the frame shell 304. The conveyor supporting struts 436 include adjustment means 440 for adjusting the overall length of the struts and, thereby, the angle of the conveyor 316.

Removably mounted within the frame shell 304, rearwardly of the cutter supporting frame 310, is a reinforcing frame 442. This reinforcing frame is similar in shape to the cutter supporting frame and includes a number of beams which are bolted to one another and to the frame shell, as shown, whereby the reinforcing frame may be removed from the frame shell. As best illustrated in FIGURE 16, the reinforcing frame is disposed in a plane normal to the axis of the frame shell.

Referring now to FIGURE 26, there is illustrated an operating or control station 444 for the tunneling machine. This control station is located in the upper half of the frame shell 304, adjacent the reinforcing frame 442, and includes a control panel 446 mounted on the latter frame. Control panel 446 is equipped with a number of valves 448 which may be manually operated to selectively control the cutter actuating rams 388, 390 and the push rams 402. Extending from the control panel 448 are a number of hydraulic lines 450 which connect the control panel valves to a hydraulic fluid supply system (not shown), the cutter actuating rams, and the push rams. The hydraulic fluid supply system of the machine is conventional and, therefore, has not been illustrated. Suffice it to say, that this supply system may include a high pressure hydraulic fluid source and a low pressure hydraulic fluid receiver embodied in a single hydraulic unit which may be located some distance from the tunneling machine and connected to the machine through a high pressure hydraulic fluid supply line and a low pressure hydraulic fluid return line. In actual practice, the control station 446 is equipped with a platform and a seat for the machine operator. This platform and seat are supported on the horizontal beam of the supporting frame 442 but have been omitted from the drawings for the sake of clarity.

The cutting elements or drag bits 352 will now be described by reference to FIGURES 12, 14 through 18, 23, 24, and 27 through 31. As best shown in FIGURES 27 through 31, each drag bit has a solid metal body 452 which may be forged or otherwise formed to the shape illustrated. This body includes a polygonal shank 454 and a generally flat cutting blade 456 extending from the front end of the shank. The drag bit shank 454 has a circumferential groove 458 adjacent its rearward end. The cutting blade 456 tapers axially of the shank to define a cutting edge 460 along the front end of the blade. The side edge portions of the blade are generally helically twisted in opposite directions, as shown, whereby the cutting edge 460 has a generally S-shape, as may be best observed in FIGURE 30.

Mounted on the front sides of the spokes 342 of the oscillatory cutters 306, 308 are a number of cylindrical socket members 462 having forwardly opening polygonal sockets 464 for slidably receiving the drag bit shanks 454 in the manner shown best in FIGURE 18. The drag bits

352 are releasably secured in their respective socket members 462 by roll pins 466 which are press fitted in bores in the socket members and engage tangentially in the drag bit shank grooves 458. Each center cutter spoke 342 mounts two parallel longitudinal rows of drag bits 352. Each outer cutter spoke mounts a single longitudinal row of drag bits which is located adjacent the outer edge of the respective spoke. The drag bits 352 in the several row of drag bits on each cutter 306, 308 are disposed with their longitudinal axes normal to the oscillatory plane of the cutters and form face cutters. Each cutter spoke 342 also mounts a single, radially outer drag bits 352a which forms a radius or gauge cutter. Each radius or gauge cutter 352a is mounted in a socket member 462a which is secured to the corresponding cutter spoke 342 with its axis inclined in an acute angle to the oscillatory plane of the cutters 306, 308, in such a way that the cutting blades 456 of the radius drag bits 352a project a small distance radially beyond the outer ends of the spokes. These radius drag bits provide each cutter 306, 308 with an effective cutting radius slightly greater than the radius of the frame shell 304, as may be best observed in FIGURE 16.

Referring to FIGURES 12 and 17, the drag bits 352, 352a are oriented on their respective longitudinal axes in such manner that the cutting blade 456 of each drag bit is inclined at an acute angle relative to the circular direction line of its oscillatory motion with the corresponding cutter 306, 308. This orientation of the drag bits, together with the unique illustrated twisted shape of the drag bit blades 456, enables the drag bits to effect an optimum cutting action in both directions of oscillation of the cutters 306, 308. The drag bits are also self sharpening to a degree in that the tapered configuration of the drag bit blades 456 acts to maintain relatively sharp cutting edges on the blades as the front edges of the blades wear in use. The drag bits 352 on the center spokes 342 of the cutters 306, 308 are offset or staggered radially of the cutters relative to the drag bits on the other spokes, as shown best in FIGURE 17. Also, the drag bits on the adjacent outer spokes of the two cutters are radially staggered relative to one another. This staggered arrangement of the drag bits prevents the latter from tracking in the grooves or kerfs cut by preceding drag bits.

At this point, it is significant to recall that the oscillation axes of the cutters 306, 308 are vertically spaced. The reason for this vertical spacing is now obvious. Thus, each cutter sweeps an effective semicircular cutting area. Accordingly, if the cutters had a common oscillation axis, as on the earlier embodiments of the invention, the combined or total effective cutting area swept by both cutters would be generally circular. On the other hand, the cross section of the frame shell 304 defined by a plane parallel to the inclined oscillation plane of the cutters is elliptical. Thus, the frontal projection, parallel to the axis of the frame shell, of the total effective cutting area swept by the cutters 306, 308, and hence the tunnel bore produced by the cutters, would not match the frontal area of the frame shell. In other words, the frontal projection of the total effective cutting area swept by the cutters, and hence the vertical cross section of the tunnel bore produced by the cutters, would be elliptical. This elliptical tunnel bore would have a horizontal width, at the center line, slightly greater than the diameter of the frame shell 304. However, the elliptical tunnel bore would have a vertical height less than the shell diameter. Accordingly, the cutters 306, 308 would leave uncut regions in front of the frame shell, adjacent the top and bottom of the shell. Conceivably, in soft formations, these uncut regions might be sheared by the front cutting edge 320 of the shell as the latter is driven forwardly during each cutting stroke of the tunneling machine. In these cases, then, the cutters 306, 308 could be mounted for oscillation on a common axis.

Preferably, however, the cutters 306, 308 are mounted to oscillate on separate axes which are vertically spaced

in such a way that the cutters sweep a generally elliptical total effective cutting area which approximately matches the elliptical cross section of the frame shell 304 in a plane parallel to the inclined plane of oscillation of the cutters. Accordingly, the frontal projection of the total effective cutting area of the cutters is generally circular and substantially matches the circular frontal area of the frame shell, whereby the cutters cut a generally circular tunnel bore sufficiently large in diameter to accommodate the frame shell. In this regard, attention is directed to FIGURES 16 and 17 wherein it will be observed that the oscillation axes of the cutters are disposed in a common vertical plane containing the central axis of the frame shell 304. It will further be observed that the oscillation axes intersect the common inclined cutting plane of the cutters at points spaced equal distances above and below the point of intersection of this plane and the central axis of the frame shell. The perpendicular spacing A between the oscillation axes is such that the sum of the spacing, the cutting radius of the cutter 306, and the cutting radius of the cutter 308 approximates or is slightly greater than the major axis of the elliptical cross section of the frame shell in a plane parallel to the cutting plane of the cutters. In addition, the rows of drag bits 352 mounted on the outer spokes 342 of each cutter 306, 308 are offset toward the outer edges of these spokes relative to the longitudinal center lines of the spokes, and each cutter oscillates through an angle of about 45° between a first limiting position, wherein one of these outer rows of drag bits on the cutter is located at one side of and substantially in a horizontal plane containing the longitudinal axis of the frame shell 304, and a second limiting position, wherein the other outer row of drag bits on the cutter is located substantially in this plane at the opposite side of the shell axis. It is evident at this point, therefore, that the two oscillatory cutters 306, 308 together sweep a generally elliptical, total or combined effective cutting area which approximately matches the elliptical cross section of the frame shell 304 in a plane parallel to the inclined plane of oscillation of the cutters. Accordingly, the frontal projection of this total effective cutting area is generally circular and approximately matches the circular frontal area of the frame shell, whereby the cutters produce a generally circular tunnel bore of a diameter large enough to accommodate the frame shell. The cutter 306 sweeps the lower half and the cutter 308 sweeps the upper half of this total effective cutting area.

The tunneling machine 300 described above is capable of several different modes of operation. In all of these different operating modes, the push rams 402 are periodically extended to drive the tunneling machine forwardly in a cutting stroke, after which the push rams are retracted and an additional section of the tunnel liner 318 is assembled within the rear tail shield of the tunneling machine. The push rams are then again extended to drive the tunneling machine forward in the next cutting stroke. This procedure is repeated, as before, until the tunnel has been driven the desired distance. Since the push rams are operated in this manner in each of the several different operating modes of the tunneling machine, these operating modes will be explained without further reference to the push rams. Moreover, in each operating mode involving operation of the lower cutter 306, the rear scraper blade 347 on the latter cutter sweeps back and forth in front of the reinforcing ring 432 and acts to aid movement of debris over the ring to the conveyor 36.

The operation of the tunneling machine 300 in one of these operating modes is similar to the operation of the earlier described embodiments of the invention. Thus, in this operating mode, the cutter actuating rams 388, 390 are pressurized to drive the cutters 306, 308 in their oscillatory motion in unison but in opposite directions. Accordingly, the cutters oscillate in unison between their

corresponding limiting positions and thereby sweep their generally elliptical, total effective cutting area, referred to earlier. This unified but reversed oscillation of the cutters 306, 308 is effective to minimize the reaction torque on the tunneling machine frame 302, as in the earlier embodiments of the invention. Preferably, however, the tunneling machine 300, like the earlier tunneling machines, is equipped with torque fins which may be laterally extended into engagement with the wall of the tunnel bore to restrain the tunneling machine frame 302 against rotation under the action of any reaction torque exerted on the frame.

In the above operating mode of the machine, the cutters 306, 308 rotate in opposite directions during each of their unified oscillatory cutting strokes. Accordingly, the cutters arrive simultaneously at their corresponding limiting positions. In an alternative operating mode of the tunneling machine 300, the cutters 306, 308 are again driven in oscillation in unison but in the same direction. In this case, the cutters rotate in the same direction during each of their unified oscillatory cutting strokes and arrive simultaneously at opposite limiting positions thereof. The rate of oscillation of the cutters 306, 308, in each of the above operating modes, may be controlled or regulated to cause the cutters to oscillate at the optimum cutting speed for each particular earth formation encountered by the tunneling machine.

In the above operating modes of the tunneling machine 300, the rate of oscillation of the cutters 306, 308 is the same. These operating modes are particularly suited for relatively homogeneous earth formations which require substantially equal cutting effort by the two oscillatory cutters 306, 308. A third possible operating mode of the tunneling machine 300 is suited for non-homogeneous earth formations which require unequal cutting efforts by the two oscillatory cutters 306, 308. In this operating mode, both cutters are driven in their oscillatory cutting motion but at different rates of oscillation. The rate of oscillation of each cutter is regulated to cause the cutter to oscillate at the optimum cutting speed for the particular earth formation in that portion of the tunnel face which is swept by the respective cutter. For example, when a non-homogeneous earth formation is encountered which presents a tunnel face having a lower relatively hard portion and an upper relatively soft portion, the lower cutter 306 may be driven at the optimum cutting speed and the upper cutter 308 may be driven at a lower speed, thus to prevent excessively rapid removal of debris of the upper, relatively soft portion of the tunnel face by the upper cutter 308. In this operating mode of the machine, then, the rates of oscillation of the two cutters 306, 308 may be adjusted to achieve a generally uniform cutting action by both cutters.

When extreme non-homogeneous earth formations are encountered, such as an earth formation which presents a tunnel face consisting, in part, of hard rock or other hard material and, in part, of loose sand or other relatively fluent material, it may be desirable to oscillate only that cutter 306 or 308 of the tunneling machine 300 which sweeps the hard portion of the tunnel face. The other cutter is retained stationary. This operation of the tunneling machine 300, therefore, involving operation of only one cutter 306 or 308 constitutes a further possible operating mode of the machine.

It will be understood, of course, that each of the above described operating modes of the tunneling machine 300 are accomplished by appropriate manipulation of the valves 448 on the control panel 446 of the tunneling machine 300. To this end, the valves are arranged in such a way as to permit selective unified or independent oscillation of the cutters 306, 308 at selectively variable speeds. Preferably, the valves which control the directions of oscillation of the cutters are arranged in such a way that these valves may be operated simultaneously to effect unified oscillation of the cutters in the same or op-

posite directions by simply moving the valve handles back and forth in unison. To this end, for example, the valve handles may be located adjacent one another in such a way as to permit these handles to be operated simultaneously with one hand for simultaneously reversing the cutters at the ends of their strokes. Alternatively, the valves may be automatically controlled by either electrical or mechanical means.

As noted earlier, the inclined oscillatory plane of the cutters 306, 308 constitutes a significant feature of the invention. Thus, it will be observed that this plane slopes forwardly in the upward direction, whereby the cutters are effective to cut an inclined tunnel face. This inclined tunnel face inhibits collapse of the face when tunneling through relatively soft formations, such as sand. In this regard, it will be recalled that the inclination of the plane of the cutters is such as to produce a tunnel face which slopes at the optimum angle of repose for many loose earth materials. This angle is on the order of 10-30°.

Another significant feature of the invention resides in the fact that the front edge of the frame shell 304 is disposed in a plane parallel to the oscillatory plane of the cutters 306, 308. This inclined front end of the frame shell provides the latter with a front upper overhang which extends over the sloping tunnel face produced by the cutters 306, 308 and supports the roof or crown of the tunnel in the region directly above the tunnel face. The tunnel wall is thereby supported against cave-in in this region.

The tunneling machine 300 has yet a further possible operating mode which may be employed when an extremely loose or fluent earth formation, such as loose sand, is encountered. In this operating mode of the machine, the entire internal cutter supporting and driving structure of the machine is removed from the frame shell 304. In this regard, it will be recalled that the cutter supporting frame 310 may be unbolted from the frame shell and disassembled to permit removal of this frame, and the cutter structure supported thereon, from the shell. Also, the cutter actuating rams 388, 390 may be detached from the frame shell and removed. A breast board 468 is then positioned within the front end of the frame shell 304, in a plane normal to the axis of the shell, as illustrated in FIGURE 32. A number of push rams 470 are also mounted within the shell in such a way as to act between the rear reinforcing frame 442 and the breast board 468 for urging the latter forwardly against the tunnel face. During operation of the tunneling machine 300 in this operating mode, the push rams 402 are periodically extended to drive the frame shell 304 forwardly through the earth formation. During this forward motion of the frame shell, the front cutting edge 320 on the shell shears the tunnel wall. The breast board 468 is retained in pressured contact with the tunnel face during each forward cutting stroke of the frame shell by means of the breast board push rams 470. This breast board is formed with a restricted opening (not shown) through which the loose debris at the tunnel face may be removed, either by hand or with the aid of a suitable powered earth mover, thus to permit the breast board to advance forwardly through the earth formation.

When tunneling through earth formations which present a non-homogeneous tunnel face composed partly of relatively hard material and partly of relatively soft material, a tunneling machine inherently tends to follow the path of least resistance and drift in the direction of the softer material. A similar situation occurs when the tunnel floor is composed of relatively soft material, since then the weight of the tunneling machine tends to cause the latter to drift downwardly with a resultant loss in grade. Failure to counteract or prevent such drift results in a progressively increasing deviation between the actual course of the tunnel and its intended course. On the other hand, in some cases drift may be deliberately introduced into a tunneling machine in order to change the course or direction of the tunnel being drilled. Various methods and

means have been devised for both counteracting undesirable drift induced by the surrounding earth formation and inducing deliberate drift in order to change the tunnel direction. According to the present invention, drift is prevented or induced, as desired, by selective radial adjustment of the gauge cutters. In this regard, it will be observed that a number of the radially inner drag bit sockets 462 on each cutter spoke 342 of the tunneling machine 300 are secured to an inner plate 472 which is rigidly attached by bolts 474 to the respective spoke. The remaining radially outer drag bit sockets on each spoke, including the socket 462a for the corresponding gauge cutter 352a, are secured to an outer plate 476 which is attached by bolts 478 to the respective spoke. Bolts 478 extend through radial slots 480 in the outer plates, whereby these plates, and hence the gauge cutters thereon, are adjustable radially of the corresponding cutters 306, 308.

Normally, the outer cutter plates 476 are secured in their inner limiting positions. In these positions, the gauge cutters 352a are set to cut a tunnel bore which is just sufficiently larger in diameter than the tunneling machine shell 304 to permit relatively free movement of the machine through the bore as the tunnel progresses. When a non-homogeneous earth formation is encountered, such as that depicted in FIGURE 33 which includes a region H of relatively hard material and an opposite region S of relatively soft material and presents a tunnel face having corresponding hard and soft regions, the gauge cutters 352a which sweep the hard formation are adjusted outwardly. The tunnel bore is thereby cut to a slightly larger radius in the region of the hard formation H than in the region of the soft formation S, as shown in somewhat exaggerated fashion in FIGURE 33. This tends to induce drift of the tunneling machine in the direction in which the tunnel bore is enlarged, i.e., toward the region H of hard material and, therefore, in a direction opposite to that in which the surrounding non-homogeneous formation tends to cause drift of the machine. The formation induced drift and the compensating drift induced by extension of the gauge cutters thus tend to counteract or neutralize one another. Accordingly, the tunneling machine may be stabilized against drift in a non-homogeneous earth formation by appropriate extension of the gauge cutters which sweep the harder region of the formation. As noted earlier, it is sometimes desirable or necessary to induce deliberate drift into the tunneling machine in order to change the course of direction of the tunnel being drilled. Obviously such deliberate drift may be induced in the present tunneling machine by appropriate extension of the gauge cutters in the desired direction of drift. It is evident, of course, that both compensating and deliberate drift of the present tunneling machine may be induced in any direction by extension of the proper gauge cutters. For example, downward drift or loss of grade of the tunneling machine resulting from relatively soft formation below the machine may be corrected or prevented by extension of the upper gauge cutters. Whenever desirable or necessary, the compensating or deliberate drift induced by extension of the gauge cutters may be augmented by operating the push rams of the tunneling machine in such a way as to exert greater thrust at the side of the machine diametrically opposite the extended gauge cutters.

Additional latitude of adjustment of the cutting radius of the gauge cutters 352a is afforded by angular adjustment of these cutters in their respective sockets 462a. In this regard, attention is directed to FIGURE 36 in which it will be observed that the effective cutting radius of each gauge cutter may be adjusted by angular adjustment of the cutter relative to its socket. The solid lines in FIGURE 36, for example, illustrate a gauge cutter in its maximum cutting radius position and the broken lines illustrate the gauge cutter in its minimum cutting radius position. The gauge cutters are retained in each of their adjusted angular positions by virtue of the mating polygonal shapes of the cutter shanks and socket bores.

The first described tunneling machines of the invention may also embody adjustable gauge cutters for the purposes just discussed. FIGURES 34 and 35, for example, illustrate a modified tunneling machine 10' according to the invention which is identical to the tunneling machine 10 described earlier except for the oscillating cutters. Thus, the modified tunneling machine 10' has coaxial oscillating cutters 24', 26' mounting cutting elements 63' in the form of drag bits like those illustrated in FIGURES 27 through 31 and polygonal sockets in which these drag bits are releasable secured. The outer drag bits that serve as gauge cutters, and a number of the adjacent drag bits, on each oscillating cutter are mounted on plates 63'' which are adjustably secured to the corresponding cutter head in the same manner as described above in connection with the tunneling machine 300 and shown in FIGURES 34 and 35. It is evident, therefore, that the gauge cutters of the tunneling machine 10' may be selectively adjusted to induce either a compensating drift into the tunneling machine to counteract a drift induced by the surrounding earth formation or a deliberate drift for the purpose of changing the tunnel direction.

At this point, a significant advantage of the present tunneling machines over the existing tunneling machines with cutting wheels which are adjustable to induce drift is worthy of note. The existing tunneling machines referred to are those having cutting wheels which may be adjusted laterally of the longitudinal machine axis to cut a tunnel bore eccentric to the latter axis and thereby induce drift of the tunneling machine in the corresponding direction. A major disadvantage of these machines resides in the fact that the gauge cutters must be adjusted outwardly when the cutting wheel is laterally displaced from the machine axis to provide sufficient clearance for the machine in the tunnel bore. When the cutting wheel rotates, of course, each gauge cutter sweeps or cuts the full circumference of the tunnel wall. As a consequence, the laterally offset cutting wheel produces a greatly oversized tunnel bore, thus resulting in an oversize annular space or void about the tunnel liner which is subsequently installed in the tunnel bore. The increased labor and material costs involved in filling this oversized void with concrete are substantial and add appreciably to the overall tunnel cost.

The present tunnel machines avoid this excessive cost factor of the existing machines. Thus, because the cutters of the present tunneling machines oscillate rather than rotate, and only those gauge cutters which sweep the region of the tunnel wall toward which drift is to be induced, a portion, only, of the tunnel wall circumference is cut to an oversized radius. As a consequence, the total volume of concrete required to fill the space between the tunnel wall and the tunnel liner which is subsequently installed in the tunnel bore, and hence the overall tunnel cost, are greatly reduced in comparison to the concrete volume and tunneling costs associated with conventional tunneling machines.

It is now obvious, therefore, that the invention herein described and illustrated is fully capable of attaining the several objects and advantages preliminarily set forth.

While the invention has herein been shown and described in what is conceived to be the most practical and preferred embodiment, it is recognized that departures may be made therefrom within the scope of the invention, which is to be accorded the full scope of the claims so as to embrace any and all equivalent devices.

Having described the invention, what is claimed as new in support of Letters Patent is:

1. In a tunneling machine, the combination comprising: a frame having a front end adapted to be progressively advanced toward a tunnel face which is to be cut; a cutting head for engaging the tunnel face and adapted for oscillatory movement in a plane parallel to the tunnel face; means rotatably mounting said cutting head on said

frame for oscillation of said cutting head in said plane;
 linear actuating means disposed in a plane parallel to said plane of oscillation and adapted for reciprocating linear extension and retraction; and
 means coupling said actuating means to said frame and to said cutting head so that said actuating means produces oscillation of said cutting head in said plane of oscillation.

2. The combination claimed in claim 1 wherein said actuating means includes a hydraulic ram.

3. The combination claimed in claim 1 wherein said actuating means includes a pair of hydraulic rams.

4. In a tunneling machine, the combination comprising:
 a frame having a front end adapted to be progressively advanced toward the face of a tunnel which is to be cut;
 a plurality of cutting heads located at the front end of said frame for engaging the tunnel face, and each being adapted for oscillatory movement in a plane parallel to the tunnel face;
 means mounting each of said cutting heads from said frame for rotatable movement independent of the others of said cutting heads;

25

a plurality of cutter actuating means, a separate one for each of said cutting heads, each including a linear actuator disposed in a plane parallel to the corresponding plane of oscillation and adapted for reciprocating linear extension and retraction; and
 means coupling each said linear actuator to said frame and to the corresponding one of said cutting heads so that the reciprocating movement of said actuator produces oscillatory movement of said corresponding cutting head in its associated plane of oscillation; said cutting heads being adapted to sweep respectively different portions of the tunnel face whereby the cutting action on individual portions of the tunnel face may be controlled independently of the cutting action on other portions of the tunnel face.

30

35

5. The combination claimed in claim 4 wherein each said linear actuator includes a hydraulic ram.

6. The combination claimed in claim 5 wherein each said cutter actuating means includes a pair of hydraulic rams.

7. In a tunneling machine including a frame having a forward end adapted to be progressively advanced toward the tunnel face, the combination comprising:
 a cutter shaft disposed substantially perpendicular to the tunnel face;
 means supporting said cutter shaft from said frame for rotary movement relative thereto;

45

50

55

60

65

70

75

a cutting head rigidly secured to the forward end of said cutter shaft, said cutter head being adapted to engage and to reciprocatingly move across a fractional portion of the tunnel face;
 cutting means secured to the forward surface of said cutting head and adapted for cutting action on the tunnel face in both directions of movement of said cutting head;
 an arcuate thrust bearing plate secured to the rear surface of said cutting head at a fixed radius distance from said cutter shaft;
 thrust roller means supported from said frame and adapted to rollingly engage said thrust bearing plate so as to support the forward thrust of said cutting head;
 a hydraulic ram including a plunger and a cylinder;
 means pivotally securing the extremity of one of said cylinder and plunger to said frame;
 means pivotally securing the extremity of the other of said cylinder and plunger to one of said cutter head and cutter shaft at a radius distance from the axis of rotation of said shaft;
 and means for extending and retracting said ram in a linear reciprocating motion so as to drive said cutting

head in an oscillatory motion through an angle less than 180°.

8. The combination claimed in claim 7 wherein said extremity of the other of said cylinder and plunger is pivotally secured directly to said cutter head.

9. The combination claimed in claim 7 which additionally includes a rigid crank arm secured to said cutter shaft and extending transversely therefrom in a direction parallel to the plane of movement of said cutting head, said extremity of the other of said cylinder and plunger being pivotally secured to the end of said crank arm.

10. The combination claimed in claim 9 wherein said crank arm is located directly behind and in close proximity to said cutting head.

11. The combination claimed in claim 7 wherein said cutter shaft support means includes a fixed shaft, and said cutter shaft includes a hub that is rotatably supported on said fixed shaft.

12. The combination claimed in claim 7 which additionally includes:

a second hydraulic ram having a plunger and a cylinder;

means pivotally securing the extremity of one of said cylinder and plunger of said second hydraulic ram to said frame;

means pivotally securing the extremity of the other of said cylinder and plunger of said second hydraulic ram to one of said cutter heads and cutter shaft at a radius distance from the axis of rotation of said shaft;

the driving connections of said first and second rams being circumferentially separated from each other relative to the longitudinal axis of said cutter shaft; and

means for drivingly extending each of said rams concurrently with the retraction of the other.

13. The combination claimed in claim 12 wherein said cutter shaft support means comprises a fixed shaft; said cutter shaft comprises a hub rotatable on said fixed shaft; and which further includes a single torque arm secured to said hub and extending transversely therefrom in a direction parallel to the plane of movement of said cutting head; one extremity of each of said hydraulic rams being pivotally connected to the outer end of said torque arm.

14. A tunneling machine according to claim 7 including:

gauge cutters mounted on said cutting head for selective radial adjustment relative to said head to induce controlled drift of the tunneling machine in a given direction, and

each gauge cutter sweeping a limited circumferential portion only of the tunnel wall, whereby the increased costs attendant to filling with concrete the enlarged void created between the tunnel wall and a liner positioned in the tunnel as a result of selective extension of the gauge cutters to induce drift are minimized.

15. A tunneling machine comprising, in combination: a frame having front and rear ends and a longitudinal axis;

a plurality of cutter shafts disposed near the front end of said frame and each being aligned generally parallel to said axis;

means supporting each of said cutter shafts from said frame in independently rotatable relationship relative thereto;

a plurality of cutting heads located at the front end of said frame, each of said cutting heads being rigidly supported from a corresponding one of said cutter shafts and being adapted for oscillation through an angle less than 180° about the longitudinal axis of its respectively associated shaft and in a plane approximately transverse to said longitudinal axis of said frame;

and a plurality of hydraulic linear actuator means for actuating said cutters, each said actuator means being secured to said frame and to a corresponding one of said cutter shafts and being adapted for extension and retraction in a direction generally transverse to said longitudinal axis of said frame so as to drivingly oscillate the respectively associated one of said cutting heads;

10 said cutting heads sweeping different, effective cutting areas and collectively sweeping a cutting area approximating the major transverse cross-section of said frame.

15 16. A tunneling machine as claimed in claim 15 wherein all of said cutter shafts are located in close proximity to said longitudinal axis of said frame, each of said cutting heads extending radially outwardly from its respectively associated shaft.

20 17. A tunneling machine as claimed in claim 15 which additionally includes means for actuating each of said actuator means independently of the others, whereby the cutting actions on different portions of the tunnel face may be controlled independently of each other.

25 18. A tunneling machine as claimed in claim 15 wherein a rigid crank arm is attached to each of said cutter shafts and extends perpendicularly outwardly therefrom, the associated actuator means being pivotally connected to the outer end of said arm.

30 19. A tunneling machine as claimed in claim 18 wherein each said actuator means includes a pair of hydraulic rams each having a cylinder and a plunger, which includes a second rigid crank arm attached to each said cutter shaft in a position circumferentially displaced from said first crank arm, one member of each of said rams being pivotally secured to said frame and the other member of each of said rams pivotally secured to the outer 35 end of a corresponding one of said crank arms.

35 20. A tunneling machine as claimed in claim 16 which additionally includes means for actuating each of said actuator means independently of the others, whereby the cutting actions on different portions of the tunnel face may be controlled independently of each other.

40 21. A tunneling machine as claimed in claim 16 wherein a rigid crank arm is attached to each of said cutter shafts and extends perpendicularly outwardly therefrom, the associated actuator means being pivotally connected to the outer end of said arm.

45 22. A tunneling machine as claimed in claim 21 wherein each said actuator means includes a pair of hydraulic rams each having a cylinder and a plunger, which includes a second rigid crank arm attached to each said cutter shaft in a position circumferentially displaced from said first crank arm, one member of each of said rams being pivotally secured to said frame and the other member of each of said rams being pivotally secured to the outer end of a corresponding one of said crank arms.

50 23. A tunneling machine as claimed in claim 17 wherein a rigid crank arm is attached to each of said cutter shafts and extends perpendicularly outwardly therefrom, the associated actuator means being pivotally connected to the outer end of said arm.

55 24. A tunneling machine according to claim 15 wherein:

60 said frame comprises an outer shell having a given frontal area; and

65 the frontal projection of the total cutting area collectively swept by all of said cutting heads approximates said given frontal area.

70 25. The combination claimed in claim 24 wherein said cutter support means are releasably secured to said frame, thus permitting removal of said cutting head means and said cutter support means from said shell; and wherein said cutter actuating means are also removable from said frame.

75 26. A tunneling machine according to claim 15 wherein:

said frame comprises an outer generally cylindrical shell having a given generally circular frontal area; said cutting heads are generally sector shaped and have contiguous axes of oscillation, whereby the frontal projection of the total cutting area collectively swept by all of said cutting heads approximates said given frontal area; and said cutting heads oscillate through different contiguous sectors, respectively, of said cutting area.

27. A tunneling machine according to claim 17 wherein:

said frame comprises an outer generally cylindrical shell having a given generally circular frontal area; said cutting heads are generally sector shaped and have contiguous axes of oscillation, whereby the frontal projection of the total cutting area collectively swept by all of said cutting heads approximates said given frontal area; and said cutting heads oscillate through different contiguous sectors, respectively, of said cutting area.

28. A tunneling machine as claimed in claim 15 wherein said cutter shafts are aligned on a common axis.

29. A tunneling machine as claimed in claim 15 wherein said cutter shafts are disposed on mutually parallel axes.

30. A tunneling machine as claimed in claim 15, which additionally includes gauge cutters mounted on each of said cutting heads for selective radial adjustment relative to said heads so as to induce controlled drift of the tunneling machine in a given direction.

31. A tunneling machine comprising, in combination: a frame having front and rear ends and a longitudinal axis, said frame including a generally cylindrical outer shell having a given frontal area centered on said axis;

a plurality of oscillatory cutters including forward cutting heads, respectively, located at the front end of said frame and disposed approximately in a common plane of oscillation substantially normal to said axis; means rotatably mounting said cutters on said frame for oscillation of said cutting heads in said plane; cutter actuating means acting between said cutters and frame for driving said cutters in oscillation, thereby to oscillate said cutting heads in said plane; said cutting heads being generally sector shaped and said cutters having a common axis of oscillation which approximately coincides with said longitudinal axis, said cutting heads sweeping a total effective cutting area having a frontal projection parallel to said axis which is generally circular and approximates the frontal area of said shell, whereby said cutters are effective to cut a tunnel bore large enough to accommodate said shell; and

said cutting heads oscillating through different contiguous sectors, respectively, of said cutting area.

32. A tunneling machine comprising, in combination: a frame having front and rear ends and a longitudinal axis, said frame including an outer shell having a given frontal area centered on said axis;

a plurality of oscillatory cutters including forward cutting heads, respectively, located at the front end of said frame and disposed approximately in a common plane of oscillation which lies at an acute angle relative to said axis;

the front end of said shell being disposed in a plane parallel to and located adjacent said plane of oscillation;

means rotatably mounting said cutters on said frame for oscillation of said cutting heads in said plane of oscillation;

cutter actuating means acting between said cutters and frame for driving said cutters in oscillation, thereby to oscillate said cutting heads in said plane;

said cutting heads sweeping a total effective cutting area having a frontal projection parallel to said axis which approximates said given frontal area of said outer shell, whereby said cutters are effective to cut a tunnel bore large enough to accommodate said outer shell; and

said cutting heads oscillating through different contiguous sectors, respectively, of said effective cutting area.

33. A tunneling machine according to claim 32 wherein:

said shell is generally cylindrical, whereby said shell has a generally elliptical cross section in a plane parallel to said plane of oscillation, and

said cutters are two in number and have their axes of oscillation disposed in a common plane containing said longitudinal axis and the major axis of said ellipse, whereby said effective cutting area is generally elliptical in shape and approximates said elliptical cross section of said shell.

34. A tunneling machine comprising, in combination: a frame having front and rear ends and a longitudinal axis;

an upper cutter shaft mounted on the front end of said frame, at a position which is approximately in the area slightly above said longitudinal axis, said upper cutter shaft as it extends forwardly being inclined somewhat downwardly at an acute angle relative to said longitudinal axis;

means rotatably supporting said upper cutter shaft from said frame;

a sector shaped upper cutting head rigidly secured to said upper cutter shaft and adapted for rotation therewith, said upper cutting head being adapted for oscillatory movement through an angle less than 180° so as to cut the tunnel face through an angle of approximately 180° at and above the elevation of said longitudinal axis;

drive means for said upper cutting head including at least one hydraulic ram having a cylinder and a plunger, said hydraulic ram being disposed approximately parallel to the cutting plane of said upper cutting head and having one end thereof pivotally secured to said frame and the other end thereof pivotally secured to one of said upper cutting head and upper cutter shaft;

means for driving said hydraulic ram in a linear reciprocating motion to thereby oscillatingly drive said upper cutting head so as to cut the upper portion of the tunnel face at an angle of inclination which will inhibit collapse of said face when tunneling through relatively soft earth formations;

at least one additional cutting head for cutting the lower portion of the tunnel face; and

drive means separate from the drive means for said upper cutting head for driving said additional cutting head.

35. A tunneling machine as claimed in claim 34 wherein in said upper cutter shaft support means includes a fixed shaft; said upper cutter shaft is a hub rotatable on said fixed shaft; and which additionally includes a torque arm extending transversely outwardly from said hub; one end of said hydraulic ram being pivotally secured to the outer end of said torque arm.

36. A tunneling machine as claimed in claim 35 which additionally includes a second hydraulic ram, one end of said second ram being pivotally secured to said frame and the other end of said second ram being pivotally secured to the outer end of said torque arm.

37. A tunneling machine as claimed in claim 35 wherein in said additional cutting head is also sector shaped, and is adapted for oscillating movement in a plane which substantially coincides with the plane of oscillating movement of said upper cutting head and through an angle less

than 180° so as to cut approximately 180° of the lower portion of the tunnel face.

38. A tunneling machine as claimed in claim 34 which additionally includes an outer shell having front and rear ends, said frame being disposed within said shell;

the upper portion of the front edge of said shell being inclined at substantially the same acute angle relative to the vertical as said upper cutter shaft is inclined relative to said longitudinal axis, the front end of said shell being also sharpened to define an earth shearing edge;

said upper cutting head and the extreme upper edge of said shell being cooperatively effective, when cutting in soft formation, for removing material which lies therebetween but which is not directly engaged by said upper cutting head.

39. A tunneling machine as claimed in claim 38 wherein in said upper cutter shaft support means includes a fixed shaft; said upper cutter shaft is a hub rotatable on said fixed shaft; and which additionally includes a torque arm extending transversely outwardly from said hub; one end of said hydraulic ram being pivotally secured to the outer end of said torque arm.

40. A tunneling machine according to claim 38 wherein the upper extremity of the forward edge of said shell has a front overhanging portion which overlies said upper cutting head when said upper cutting head is in its most elevated position.

41. A tunneling machine according to claim 38 including:

a breast board positioned within the front end of said shell in a plane transverse to the axis of said shell for reinforcing the tunnel face,

hydraulic rams acting between said shell and breast board for urging said breast board forwardly against the tunnel face, and

said breast board having a restricted opening through which debris may be removed from the tunnel face.

42. A tunneling machine comprising, in combination:

a frame having front and rear ends;

a number of separate cutters mounted on the front end of said frame, said cutters collectively being adapted to sweep a total effective cutting area on the tunnel face, each of said cutters individually being adapted to sweep a different individual portion of said total effective cutting area;

separate means for driving each of said cutters independently of the others, whereby the cutting actions on the different individual portions of the tunnel face may be controlled independently of each other; and each of said cutter driving means including a hydraulic linear actuator adapted for linear extension and retraction in a direction transverse to the longitudinal axis of said frame so as to drivingly oscillate the respectively associated one of said cutting heads through an angle less than 180°.

43. A tunneling machine according to claim 42 wherein:

said frame includes an outer shell having a given frontal area, and

said effective cutting area has a frontal projection parallel to the axis of said shell approximating said frontal area.

44. A tunneling machine according to claim 42 which additionally includes a plurality of cutter shafts, one for each of said cutters, each of said cutter shafts being aligned generally parallel to the longitudinal axis of said frame; at least one said cutter shaft having a crank arm extending transversely therefrom, one end of the associated hydraulic linear actuator means being pivotally coupled to the end of said crank arm and the other end thereof being pivotally secured to said frame.
